UNITED STATES PATENT OFFICE.

EMMETT McCARRELL, OF BEDFORD, INDIANA.

SAMPLE-DISPLAYING DEVICE.

1,119,087.

Specification of Letters Patent.

Patented Dec. 1, 1914.

Application filed December 3, 1913. Serial No. 804,414.

REISSUED

To all whom it may concern:

Be it known that I, EMMETT McCARRELL, a citizen of the United States, residing at Bedford, in the county of Lawrence and 5 State of Indiana, have invented certain new and useful Improvements in Sample-Displaying Devices, of which the following is a specification.

The invention relates to sample displaying devices, and has for an object to provide 10 a device for displaying cloths or goods to a prospective purchaser of a suit or the like, in a manner which will represent the cloths or goods as they would appear if made up in 15 the form of a suit.

The invention contemplates, among other features, the provision of a device of a simple and durable construction, wherein cloths or goods can be readily and quickly 20 arranged to appear as if they were made up into suitings, and wherein furthermore, the representations of the suitings will appear in relief and have the effect of being actually applied to the body of a person.

25 In the further disclosure of the invention, reference is to be had to the accompanying drawings, forming a part of this specification, in which similar characters of reference denote corresponding parts in all the 30 views, and in which,

Figure 1 is a front elevation of the device, with the goods displayed therein; Fig. 2 is a vertical sectional view, taken on the line 2—2 in Fig. 1; Fig. 3 is a rear elevation of 35 the framing member, removed from the base or stand; Fig. 4 is a front elevation of the backing, removed from the base or stand; Fig. 5 is a horizontal transverse sectional view, taken on the line 5—5 in Fig. 4, and 40 Fig. 6 is a horizontal transverse sectional view, taken on the line 6—6 in Fig. 4.

Referring more particularly to the views, I provide a base or stand 10, preferably made of a strap like metal, to form forwardly projecting stop flanges 11, and rearwardly inclined uprights 12, secured near their free upper ends by suitable braces 13, forming a part of the base or stand. The 45 said base is carried on swiveled casters 14, so that the same can be conveniently rolled or pushed over a floor to arrange the device in exhibiting position before the prospective purchaser.

50 Mounted to swing on the lower portions of the uprights 12 is a framing member 15, adapted to have its lower edge 16 abut

against the forwardly projecting flanges 11, when the said framing member is swung forwardly upon the base 10, so that the forward swinging movement of the framing member will be limited by the flanges 11, and prevent the base from toppling over. The framing member 15 is preferably of a rectangular configuration and has a cut-out portion 17 simulating the general configuration or outline of a suit. Pictures 18, representing a face, hands, shoes, collar and tie, are pasted or otherwise placed upon the front face of the framing member 15, to conform to the cut-out portion 17, as clearly 60 shown in Fig. 1, and carried on the body of the framing member are wire-like members 19 projecting into and across the cut-out portion 17 to indicate the general lines and details of a garment, such as a coat.

A backing 20 is rigidly supported on the uprights 12, and is preferably made of wood, papier-mâché, or pressed metal, to resemble the general outlines of a person's body, with the configuration of the backing being similar to that of the cut-out portion 17, so that the backing can be fitted into the said cut-out portion. The design of the backing is clearly shown in Fig. 4, and by referring also to Figs. 5 and 6, it will be seen that the 70 front surface of the backing has a series of integral portions 21, set out in relief, to indicate the lines of creasings of the suit as the same will appear when actually made up. A locking member, of any preferred 75 type, is mounted to swing upon the rear face of the framing member 15, and is indicated by the numeral 22, said locking member being adapted for engagement with the backing 20 to hold the same rigid relatively to 80 the framing member, when the device is in 85 exhibiting position.

In the use of the structure described, I will assume that a prospective purchaser of a suit desires to view the goods or cloth, characterized by the numeral 23 in the views, as it 90 would appear when made up into a suit. To accomplish the effect, the locking member is disengaged from the backing 20 and the framing member is swung forwardly to lie 95 in spaced relation to the backing and provide sufficient space to permit of inserting the goods 23 between the framing member and the backing. When this has been done, the framing member is swung back to its 100 normal position, thus causing the goods to 105 appear through and extend into the cut-out.

portion 17. The locking member, having been reengaged with the backing 20, it will be apparent that the portions 21 of the backing, projecting into the cut-out portion of 5 the framing member, will fold or crease the goods, covering the same, so that the goods will stand out in relief and have the defined 10 lines of a finished suit as it would appear upon the body of a person, and the members 15 19, lying in front of the goods, will complete the resulting simulation by clearly defining those portions of the goods which are adapted to represent the sleeves, lapels, collar and breastings of the coat or other garment. 20 Thus it will be seen that the pictures 18, on the framing member 15, and which as a whole will represent a mounting, taken in conjunction with the goods 23, set forth as mentioned, will present a figure having the 25 simulation of a person attired in a tailored suit, and in which various parts of the garments will appear as they would when actually covering the limbs of a person.

Having thus described my invention, I 25 claim:

1. In a sample displaying device, the combination with a base, of a backing adapted to have fabric placed over its face, said backing having portions thereof formed in relief on the face of the backing, a framing member having a cut-out portion simulating the outline of the body, with the portions of the backing in relief adapted to lie in the

cut-out portion of the framing member, and wire-like members on the framing member 35 and lying within the plane of the cut-out portion to press against the fabric so that those portions of the fabric covering the portions in relief on the backing will be pressed forwardly adjacent the said members. 40

2. In a sample displaying device, the combination with a base, of a framing member mounted to swing thereon and provided with a cut-out portion simulating the outline 45 of the body, a backing carried by the base and having portions thereof set out in relief on the face of the backing, with the said portions adapted to project into the cut-out portion of the framing member, said backing being adapted to have a fabric placed over its face and be visible through the cut-out portion of the framing member, and means on the framing member and lying within the plane of the cut-out portion, 55 said means being adapted to press against the fabric so that the portions of the fabric covering the raised portions on the face of the backing will stand out in relief adjacent the said means.

In testimony whereof I affix my signature in presence of two witnesses.

EMMETT McCARRELL.
